(57) **CLAIM**

The ornamental design for an emergency power supply housing, as shown and described.

DESCRIPTION

FIG. 1 is a front, right and top perspective view of an emergency power supply housing, showing our new design; FIG. 2 is a rear, left and bottom perspective view thereof; FIG. 3 is a perspective view, shown in an opened condition; FIG. 4 is a front view thereof; FIG. 5 is a rear view thereof; FIG. 6 is a left side view thereof; FIG. 7 is a right side view thereof; FIG. 8 is an enlarged top plan view thereof; and, FIG. 9 is an enlarged bottom plan view thereof. The broken lines shown in the drawings illustrate portions of the emergency power supply housing that form no part of the claimed design.
